Frank H. Allen.

UNITED STATES PATENT OFFICE.

JOHN STEINER, OF NORWICH, CONNECTICUT.

TOY.

SPECIFICATION forming part of Letters Patent No. 364,553, dated June 7, 1887.

Application filed September 25, 1886. Serial No. 214,508. (No model.)

To all whom it may concern:

Be it known that I, JOHN STEINER, a citizen of the United States, residing in the city of Norwich, county of New London, and State 5 of Connecticut, have made certain new and useful Improvements in Toys, which improvements are fully set forth and described in the following specification, reference being had to the accompanying drawing, which is a side 10 elevation of my device with its elementary parts properly assembled.

My invention is in that class of toys adapted to whirl continuously in a given direction; but instead of spinning on a table or on the 15 ground, as in the case of tops, it rotates within an auxiliary section held by the operator, as hereinafter described in detail.

My device also differs from tops in the fact that it may be kept in motion any desired 20 length of time, while in the case of the top the duration of rotation must be limited.

Referring to the annexed drawing, the letter *a* indicates a shell of general spherical outline, perforated through its vertical center to 25 receive a stem, *b*. This stem has securely fixed to its upper end a ball, *c*, of glass, metal, or similar heavy material, and at its lower end is provided with a pin or enlarged head, as shown, to prevent its being withdrawn from 30 the shell. Shell *a* is also perforated at opposite sides to receive a string, *d*, which enters a shell at one side, is carried one turn around stem *b*, and passes out through the opposite side of the shell. To one end of string *d*, I 35 attach a weight, *e*, and to the other end, preferably, a ring, *h*, as shown, although a simple knot would serve to prevent the withdrawal of the string.

When it is desired to use my device, the 40 shell *a* is held between the thumb and index-finger of one hand and the ring or string is grasped by the other hand. By drawing the hand outward, in the direction indicated by arrow No. 1, the string clasps stem *b* firmly 45 enough to rotate both it and the enlarged portion *c*. After having drawn the string its full length the right hand is brought quickly back toward the shell, when weight *e* draws the string in the direction of arrow No. 2 to take 50 up the slack portion. During this return movement the hand of the operator moves much more rapidly than the weight *e*, and the

string slips loosely around stem *b*, with no tendency to check the momentum first attained.

The movements described are repeated as 55 long as it is desired to keep the ball *c* in motion.

The weight *e* may be of any suitable material and of any desired form.

The shell *a*, I find in practice gives a fairly 60 satisfactory result when made of soft cast metal; but I have also discovered that a large filbert or hazelnut, as shown, meets all the conditions of the case much better, and I have therefore adopted it. The metal, if hard, cuts the string, 65 and if soft, soon blackens it, but the filbert-shell neither wears the string perceptibly nor discolors it. It has also the desirable qualities of cheapness and novelty to recommend its use.

It will be noted that in the construction de- 70 scribed the head *c* and its stem rotate continuously in the same direction, instead of traveling alternately to the right and left hand, as in the case of ordinary buzzes and whirligigs.

I am aware that the prior art shows a whirligig in which a stem is used, having a string with one end secured thereto and adapted to alternately wind around said stem and unwind therefrom, for the purpose of rotating said stem alternately in opposite directions. Said device also shows a shell by which it may be supported and within which the string winds around the stem. In view of such prior art, I do not broadly claim a sup- 80 porting-shell, a stem adapted to rotate therein, and a string for imparting motion to said stem. 85

Having described my particular invention and the manner in which it is operated, I claim as new and desire to secure by Letters Patent— 90

The within-described toy, consisting of a shell-section perforated vertically and laterally, as described, a rotatable head having a stem adapted to pass through the said vertical perforation, and a string passing laterally 95 through the shell and coiled about said stem, said string being weighted at one end, substantially as herein described, and for the purpose set forth.

JOHN STEINER.
